US00D941716S

(12) **United States Design Patent** (10) Patent No.: **US D941,716 S**
(45) Date of Patent: **** Jan. 25, 2022**

(54) **VEHICLE REAR LOWER BUMPER COVER**

- (71) Applicant: **Ford Global Technologies, LLC**, Dearborn, MI (US)
- (72) Inventors: **Soohyoung Kim**, Northville, MI (US); **Thomas Marminc**, Ferndale, MI (US); **Damon G. Depyster**, Northville, MI (US); **Gordon M. Platto**, Troy, MI (US)
- (73) Assignee: **Ford Global Technologies, LLC**, Dearborn, MI (US)
- (**) Term: **15 Years**
- (21) Appl. No.: **29/728,253**
- (22) Filed: **Mar. 17, 2020**

(57) **CLAIM**

The ornamental design for a vehicle rear lower bumper cover, as shown and described.

DESCRIPTION

FIG. 1 is a front elevational view of a vehicle rear lower bumper cover, showing our new design;
FIG. 2 is a left side elevational view thereof;
FIG. 3 is a right side elevational view thereof;
FIG. 4 is a top plan view thereof;
FIG. 5 is a bottom plan view thereof;
FIG. 6 is a bottom, front and left side perspective view thereof; and,
FIG. 7 is a top, front and left side perspective view thereof.

1 Claim, 7 Drawing Sheets
